ATTORNEY

UNITED STATES PATENT OFFICE

WALTER HAMILTON DELAHAYE, OF OTTAWA, ONTARIO, CANADA, ASSIGNOR TO BEN-DIX BRAKE COMPANY, OF SOUTH BEND, INDIANA

BRAKE

Application filed May 1, 1929. Serial No. 359,446.

This invention relates to an improved type of brake, and particularly those adapted for an automobile, which have the shoes so arranged that movement of one shoe causes the remaining shoes to be applied with an increased pressure. Such brakes are termed "Servo" or "self-energizing" brakes and it is the object of the invention to provide an improved construction of such Servo brakes.

One of the objects is to provide a brake which is fully effective when the wheel is at rest and a secondary object is to provide for a Servo action for both directions of rotation of the wheel. Another advantage in the construction about to be disclosed is that the trailing shoe is applied with greater force than the reversely acting shoe which lessens the tendency of the latter shoe to grate when applied.

The construction of the brake will now be described with reference to the accompanying drawing in which

Figure 1 is an elevation of the preferred form of brake, the shoes being shown applied, but in the position occupied prior to any Servo action;

Figure 2 shows a modified form of Servo shoe; and

Figure 3 is a section on line 3—3 of Figure 2.

In the drawing all return springs and stops have been omitted but it is obvious that such must be used. Their construction, however, may vary and it is well within the capability of any skilled mechanic to construct these. The gist of the invention lies in the means for applying the force created by the Servo shoe to the main shoe.

Reference numeral - indicates a brake drum and 2 the customary flange on the axle which is indicated at 3. The brake consists of two similar shoes 4 mounted on fixed pivots 4' and a secondary shoe 5. This shoe 5 is the Servo shoe and it is so mounted that it has certain amounts of movement in both directions between the pivots 4'. The shoes 4 are of the construction usually employed in internal expanding cam brakes, but a novel means for operating these from the Servo shoe is provided, and they are necessarily

shorter than usual to provide space for the Servo shoe.

Instead of the customary cam the shoes 4 have between them the end of a lever 6 which has a straight portion 7 lying between the bearing surfaces 8 of the shoes 4. The lever 6 is provided with a collar 9 also bearing on the inner ends of the bearing surfaces 8 and from here the lever continues diametrically across the flange 2, being provided with an offset 10 to allow sufficient lateral movement to the lever. On the free end of the lever is telescopically mounted the Servo shoe 5, a sliding joint being provided. In the drawing this is shown as a tubular socket 11, but any type of sliding joint may be provided. The end of the tubular socket is provided with a bearing surface 12 adapted to contact with a cam 13 which is mounted on a rock shaft 14 journalled in the lever 6. This rock shaft passes freely through an arcuate slot 15 in the flange 2 and is provided with the customary short lever 16 of the regular brake rigging.

It is, of course, understood that all the shoes carry the customary brake lining 117 and while they are shown of the rigid T-section type this is not necessary and any other type may be used.

The operation of the device although self-evident will now be briefly set forth. When the operating lever 16 causes rotation of the rock shaft 14, the cam 13 engages the surfaces 12 and forces the Servo shoe 5 against the brake drum 1. However, as the lever 6 is floating the reaction of the cam also forces the lever in the opposite direction so that the collar 9 engages the ends of the brake shoes 4 and forces them outwardly against the drum 1. It will thus be seen that the brake shoes are all applied even if no Servo action takes place so that for holding the car stationary the construction has all the advantages of an ordinary brake. This is not true of many Servo brakes.

When the shoe 5 engages the drum 1 which is rotating it is necessarily carried with it as it is provided with no fixed anchorage. But any movement will cause the lever 6 to swing so that the portion 7 between the bear-

ing portion 8 on the shoes 4 presses these shoes apart. Thus the applying force of the lever 6 due to the diametrical movement exerted by the collar 9 is greatly augmented by its swinging movement. As this latter movement is in proportion to the speed of rotation of the drum 1 it will be understood that as the speed lessens the brake pressure is decreased. Such operation decreases the tendency of the wheels 10 to lock which at times is very dangerous.

Referring to Figure 2, a modified form of Servo shoe is shown. Instead of a Servo shoe 5 slidably mounted on the lever 6 the latter carries two Servo shoes 5' pivoted at 17 on the lever. These shoes present a drum-engaging surface 18 and also two cam engaging surfaces 19 lying on opposite sides of the cam. Instead of the single lobed cam 13 a double lobed cam 20 is employed. The operation of 15 the device is similar to the form described above and therefore repetition is deemed unnecessary.

The above sets forth examples embodying applicant's invention, but various changes 20 may be made without departing from the spirit of the invention. It will be seen that as the lever swings the pressure of the collar 9 will increase on the end of the trailing shoe, but will be lessened on the reversely acting 25 shoe, the advantage of which has been previously explained.

It is the intention of the applicant to cover the invention broadly including such modifications as may come under the scope of the 30 appended claims.

What I claim is:

1. In a Servo brake, a fixed support, a main shoe, a lever operating said main shoe, a Servo brake shoe slidable on said lever and 35 means supported on said lever to cause outward movement of said shoe to engage a brake drum.

2. In a brake as claimed in claim 1, said Servo operating means consisting of a cam 40 journaled in said lever, said journal extending outwardly through an arcuate slot in said support and being provided with an operating lever.

3. In a brake and in combination with a 45 fixed support, a pair of anchored shoes extending over a major portion of the periphery of the brake, the adjacent ends of said shoes being free, a Servo shoe occupying the minor portion of the periphery of the brake 55 and means for simultaneously urging the Servo shoe and the free ends of the anchored shoes radially outwards.

4. In a device as claimed in claim 3, said 60 means being adapted on engagement of the Servo shoe to also apply a circumferential expanding force to the free ends of the anchored shoes.

5. In a device as claimed in claim 3, said 65 means consisting of a lever slidably engaged

between the free ends of the anchored shoes and slidably supporting the Servo shoe.

6. In a device as set forth in claim 3, said means consisting of a floating lever, slidably engaging the free ends of said anchored shoes, a stop on said lever engaging said free ends, said Servo shoe being mounted on the other end of said lever and lying between the anchored ends of the shoes, and a cam carried on said lever engaging said Servo shoe, the reaction from said cam causing said stop to engage the free ends of the shoe. 70

7. In a Servo brake and in combination with a support, a pair of oppositely extending anchored shoes and a Servo shoe lying 75 between said anchors, the free ends of the anchored shoes presenting opposed bearing surfaces lying in a radial plane, a diametrically disposed floating lever between said free ends, the Servo shoe being slidably mounted on the other end of said lever, said Servo shoe having a socket formed therein to provide said slidable mounting, said socket presenting a cam-engaging portion to cooperate with an operating cam carried by 80 said lever.

8. In a brake, a support, a pair of shoes anchored on said support, the free ends of said shoes presenting opposed bearing surfaces, a brake drum cooperating with said 85 shoes, a lever between said surfaces extending diametrically of the drum to the opposite side thereof, a Servo shoe, and means for causing said Servo shoe to engage the brake drum, said Servo shoe causing movement of the lever upon engagement with the drum during the braking operation, and said lever having a radial thrust transmitting portion engageable with the free ends of said pair of shoes. 100

9. In a brake, a support, a pair of shoes anchored on said support, the free ends of said shoes presenting opposed bearing surfaces, a brake drum cooperating with said 105 shoes, a lever between said surfaces extending diametrically of the drum to the opposite side thereof, a Servo shoe, and means carried by said lever for creating a thrust upon the Servo shoe to cause it to engage the brake drum, said Servo shoe causing movement 110 of said lever upon engagement with the drum during the braking operation.

In testimony whereof I have affixed my signature.

WALTER HAMILTON DELAHAYE. 120
